UNITED STATES PATENT OFFICE

2,537,618

ELECTRIC CIRCUIT BREAKER

William George Bourne, Acton, London, England,
assignor to Rotax Limited, London, EnglandApplication January 26, 1948, Serial No. 4,272
In Great Britain December 16, 1946Section 1, Public Law 690, August 8, 1946
Patent expires December 16, 1966

2 Claims. (Cl. 200—98)

1

This invention has for its object to provide an improved electric circuit breaker of simple and robust construction.

In the accompanying drawings,

Figure 1 is a front elevation, partly in section, of a three-phase circuit breaker constructed in accordance with the invention;

Figure 2 is a sectional side elevation of the circuit breaker;

Figure 3 is a fragmentary side elevation showing a part of the closing toggle mechanism.

In one convenient embodiment of the invention as illustrated in a three-phase alternating current circuit breaker there is provided a body or base 1 of suitable insulating material and on this are secured three fixed contacts 2. Adjacent to these contacts is arranged an arm 3 which is pivoted at one end at 4 to brackets 5 secured on the body part 1 and the said arm at the other end carries three corresponding movable contacts 6. The latter may be mounted directly on the arm, but preferably they are carried by spring-loaded fingers 7 pivotally mounted on the arm at 8. Flexible conductors 9 connect the contact arms 3 to terminals 10 on the base. For moving the arm 3 to its closed position there is provided a toggle link device which comprises links 11 and 12 pivoted together on a pin 13, the links being preferably duplicates. The outer end of the link 11 is pivotally attached to the arm 3 at 14, and the outer end of the link 12 is pivotally attached at 15 to one end of a lever 16 which itself is carried on the brackets 5 by a pivot 17 situated between the ends of the lever. The toggle links are loaded by a pair of helical springs 18 which bear at one end on sub-brackets 19 on the main brackets 5 and at the other end on collars 20, secured to links which are pivoted at 21 to the arm 3. In association with the toggle links 11, 12 is arranged an electromagnet 22 of the solenoid type the plunger 23 of which is connected by a link 24 with the junction 13 of the toggle links, the said link being formed with a slot of suitable length to provide a lost-motion connection with the toggle links. Also at the electromagnet side of these links is arranged a spring stop-blade 25 which may (and preferably) form part of a switch having contacts 25¹ for controlling the circuit of the winding of the electromagnet 22, and which also serves the purpose hereinafter described. The blade 25 is arranged to be actuated by a roller 26 on an extension of the pivot 13 joining the two toggle links.

A second toggle device is provided comprising links 27 and 28 pivoted together at 29 and loaded

2

by a spring 30. The outer end of link 28 is pivotally mounted at 31 on a bracket secured to the body or base and the outer end of the link 27 is pivotally connected at 32 to the other end of the lever 16. Adjacent to the junction of these links is mounted a spring blade 33 which at one end bears on the link 27 and at the other end is anchored to the link 28. It will be understood that the links 27, 28 are preferably duplicated and are connected by the common pivot pin 29. Also in association with these links is arranged a spring loaded trip lever 34 pivoted at 35 and carrying a stud 36 arranged to bear upon the pivot pin 29. The free end of this lever 34 is connected to the plunger 37 of a second electromagnet 38 of the solenoid type. Windings 39 in series with the main switch contacts surround cores 40 arranged to act upon an armature 41 carried on a pivoted lever 42 of bell-crank form, one arm 20 of which engages a pair of spring blades 43 one of which carries a movable contact 43¹ for engagement with a fixed contact 44 when the lever is actuated. These contacts are in the circuit of the electromagnet 38. A push button 45 is also 25 provided engaging a bell-crank lever 46 pivoted at 47 and loaded by a spring 47. The other arm of this lever comprises a pair of parallel members 48 arranged, when the button 45 is depressed, to engage the pivot pin 29 of the second toggle device.

A circuit breaker as described above may be closed by a manually operable switch of, for example, the push button type arranged in the circuit of the electromagnet 22 connected to the first toggle device. When the breaker is open as illustrated, the toggle links 11 and 12 occupy a V relationship and the links 27, 28 of the second toggle device are almost in alignment with each other, being in fact slightly beyond their dead-centre position and being maintained in this condition by the spring blade 33 which acts on them. The links are prevented from further outward movement in a direction to break the toggle by the spring blade 33. In this position the links 27, 28 30 provide an anchorage for the lever 16 which is thereby held in stationary relation to the fixed bracket structure. To close the breaker the appropriate switch is actuated for closing the circuit of the electromagnet 22. By the action of this electromagnet the toggle links 11, 12 are straightened out and moved slightly beyond their dead-centre position, causing the contact arm 3 to be rocked to the closed position and bringing the main contacts 6 into engagement with their 35 associated fixed contacts. This action brings the

roller 26 into engagement with the spring blade 25 and breaks the contacts 25¹ which interrupt the circuit of the electromagnet 22, so that the closing of the breaker requires only a momentary operation of the electromagnet. On interruption of the electromagnet circuit the plunger 23 returns to its initial position without affecting the toggle links, by reason of the lost motion afforded by the slot in the link 24.

To open the breaker the push button 45 is depressed. This causes the arms 48 of the lever 46 to engage the pivot pin 29, thereby collapsing the links 27, 28 of the second toggle device and causing them to assume a V relationship. As a result the lever 16 connecting the two toggle devices is released so that the toggle links 11, 12 no longer have a fixed anchorage at 15 and the toggle is broken. This is effected by the combined action of the spring blade 25 which urges the links to the opposite side of their dead-centre position and the helical springs 18 which rock the arm 3 to a position in which the main contacts are opened. Upon release of the push button 45, the spring 30 acting on the toggle links 27 and 28 restores these and the lever 16 to their initial position, and the breaker is then in condition to be re-closed when required.

In the event of an overload, the armature 41 is actuated, thereby causing the circuit of the electromagnet 38 to be closed to actuate the latter and thereby result in the collapsing of the second toggle device and initiating the sequence of actions involved in the opening movement of the breaker described above. It will be appreciated that a push button or other switch may be provided in place of or in addition to the push button 45, such switch being arranged in an appropriate circuit for energising the second electromagnet 38 to effect the opening of the breaker when required.

Having thus described my invention which I claim as new and desire to secure by Letters Patent is:

1. An electric circuit breaker comprising in combination at least one fixed contact, at least one movable contact, a pivoted arm carrying the movable contact, a lever pivoted at a position intermediate its ends on a fixed axis, a pair of spring loaded toggle links respectively pivoted at

their opposite ends to the arm and one end of the lever, means for actuating the toggle links to move the arm in the direction for closing the contacts, a second pair of spring loaded toggle links which at their opposite ends are respectively provided with a fixed anchorage and pivoted to the other end of the lever, and means including an electromagnet for actuating the second toggle links to move the arm through the medium of the lever and the first mentioned toggle links in the direction for opening the contacts.

2. An electric circuit breaker comprising in combination at least one fixed contact, at least one movable contact, a pivoted arm carrying the movable contact, a lever pivoted at a position intermediate its ends on a fixed axis, a pair of spring loaded toggle links respectively pivoted at their opposite ends to the arm and one end of the lever, an electromagnet for actuating the toggle links to move the arm in the direction for closing the contacts, said electromagnet having a lost-motion connection with the toggle links, a switch operable by the toggle links for controlling the electromagnet, a second pair of spring loaded toggle links which at their opposite ends are respectively provided with a fixed anchorage and pivoted to the other end of the lever, and means including a second electromagnet for actuating the second toggle links to move the arm through the medium of the lever and the first mentioned toggle links in the direction for opening the contacts.

WILLIAM GEORGE BOURNE.
